UNITED STATES PATENT OFFICE.

JULIUS HEUSSER, OF ST. CROIX FALLS, WISCONSIN.

CHAIR ATTACHMENT.

1,279,692.

Specification of Letters Patent. Patented Sept. 24, 1918.

Application filed February 21, 1918. Serial No. 218,525.

To all whom it may concern:

Be it known that I, JULIUS HEUSSER, a citizen of the United States, residing at St. Croix Falls, in the county of Polk and State 5 of Wisconsin, have invented certain new and useful Improvements in Chair Attachments, of which the following is a specification.

This invention relates to furniture, and more especially to book holders which are 10 supported at their base and are adjustable; and the object of the same is to produce an attachment to an ordinary chair by means of which the occupant thereof may support a book or the like in front of him, or a table 15 or stand which is adjustable, and by means of which he may change the position of said table so as to do writing thereon.

A further object is to improve the details of construction of such a device so as to facilitate the adjustment of parts and amplify 20 the uses of the whole.

Details are brought out in the following specification, and reference is made to the drawings, wherein:—

25 Figure 1 is a side elevation of an ordinary Morris chair with this attachment applied to its arms,

Fig. 2 is a front elevation of the book holder as it appears to the user,

30 Fig. 3 is a bottom plan view,

Fig. 4 is a transverse sectional view through the book holder or table and the supporting means therefor,

Fig. 5 is an enlarged upright sectional 35 view through one of the supports,

Fig. 6 is a detail of one of the ink well holders,

Fig. 7 is a plan view in detail of one of the hanger plates,

40 Fig. 8 is a perspective detail showing the cord fastener,

Fig. 9 is a plan view of the interior of the table,

Fig. 10 is a detail of the leg attachment,

45 Fig. 11 is an end view of the table, showing the same folded down to the arm of the chair.

The type of chair to which this attachment is applied is not essential, excepting 50 that it is most convenient that it shall have arms herein designated by the numeral 1. In Fig. 5 is shown a metal-lined socket 2 in one of said arms, and seated therein is the shank 3 of a fork whose arms 4 rise above 55 the chair-arm and are given the configuration best seen in side elevation in Fig. 1.

Pivoted at 5 between the fork-arms is the base 6 of a support 7 which is of U-shaped cross section as best seen in Fig. 4, and this base is provided with a bolt 8 which moves 60 in arcuate slots 9 struck in the fork-arms 4 around the pivot bolt 5, while an appropriate tightening device 10 is located on one end of the bolt 8 so that after the base has been adjusted to the proper angle it may be 65 clamped between the arms 4 by manipulating said tightening device in a manner which will be clear. Above the fork the support 7 is of U-shaped section as has been stated, and slidably mounted thereon is a runner 70 11 which is also of U-shaped cross section with fingers 12 hooked around the back of the support so that these two elements may not become disconnected although the runner may slide on the support. Pivoted at 75 13 to the upper end of each runner is a hanger plate 14 whose configuration is best seen in Fig. 7, and in the body of this plate is an arcuate slot 15 which moves on a stud bolt 16 carried by the lower end of the runner as seen in Fig. 5. A tightening device 17 is mounted also on the stud bolt inside the plate 14 and outside a pin 18 through the inner end of the bolt, and this device also may be of any appropriate construction. 80 I might here say that the tightening devices herein illustrated are composed of spiral cams rotatably mounted on the bolts which support them and having radial arms by which they may be turned on said support 90 to move their bodies longitudinally on the bolts and tighten the members carried thereby; but it is obvious that other forms of tightening devices may be employed. The 95 arcuate slot 15 in the hanger plate is quite ample and the result is that the parts carried thereby may be swung for a considerable distance around the pivot 13; and the adjustment permitted may be used in addition to the adjustment of the support 7 100 around its pivot 5, or not, as preferred.

As an addition or refinement, I may use at the lower end of each runner between it and the hanger plate a brake element consisting of a right-angular member whose body 19 is slidably mounted on the stud-bolt 16 and whose foot 20 constitutes a shoe adapted to bear against the support 7 and frictionally sustain the parts in their adjusted position; and this brake is held in contact with the plate 14 by the same tightening mechanism 17 just described, 105 110

Mounted on the bolt 13 at the upper end of the hanger plate and on a bolt 23 at the lower end thereof, are short hinge leaves 21 as best seen in Fig. 4, the long leaves 22 thereof at one side of the attachment extending directly toward the corresponding long leaves at the other side of the attachment and being slotted as at 24. These long leaves are slidably mounted in channel bars 25 secured to the bottom of two panels 26 of which the book-rest or table top is made up, and where they meet at the center of the same they may well be hinged at 27 so as to connect their channels. Set screws 28 pass through the slots 24 and through the bars 25 and into the panels, to permit adjustment of parts. By this construction it is obvious that if the arms 1 of the chair are quite far apart the long leaves will be slid outward in 20 the channel-bars, and vice versa, and therefore the attachment is applicable to a wide variety of chairs now on the market. By loosening the tightening device 10 at each side, the support 7 may be adjusted angularly with relation to the forks 4, and therefore the entire device may be tilted from the reader or swung up toward him, or might in fact be let clear down to almost a horizontal position as seen in Fig. 11 in case he desires 25 to use the device for writing purposes. By loosening the tightening device 17, the angle of the book-rest or table to the support can be adjusted in a manner which will be clear, and this adjustment is independent of the 30 adjustment of the support within the fork. At any time when the attachment is not desired on the chair, the shanks 3 of said forks are pulled out of the sockets 2, this entire device folded into a small compass, and laid 35 40 away.

I prefer to make the table top in what might be called a box shape as perhaps best seen in Figs. 4 and 9, and the panels 26 referred to above constitute the bottom of this 45 box. The top of the box-like table may well be in two shallow sections 30 hinged at 31 to the upper ends of the panels and adapted to fold down over them, and the sections will have surrounding flanges 32 which eventually form the walls of the box-like top. The 50 panels 26 may have upstanding flanges, shown in Fig. 9 at the left as surrounding one panel at the right and sub-dividing the other into compartments, and numbered respectively 33 and 34. Rising from the upper 55 sections 30 near their lower edges are ledges 35 for supporting books and the like when the table stands practically upright. An ink-well support (see Fig. 6) may be employed, here shown as consisting of a ring 36 and a link 37 by means of which it is connected to the table so that it may overlie the same as seen in Figs. 2 and 11, or be folded under the same as seen in Figs. 1 and 3. 60 Finally a cord 38 having knots 39 is at-

tached at one end at the point 40 to one edge of the table as seen in Fig. 2, led over the same so as to hold the leaves of the books open, and passed at the other side of the table through a fork 41 whose arms are 70 spaced to receive the cord but not to permit the passage of the knots.

An amplification of which the device is susceptible is shown in Fig. 10. This consists of the use of a leg 44 having a caster 75 or other form of a foot 45 at its lower end, its upper end being adjustably mounted through an eye 46 in a rigid arm 47 which is preferably square in cross section and is passed through a hole 48 in either one of the 80 arms 4 of the fork, somewhat in rear of the arcuate slots therein. A set screw 49 serves the purpose of permitting vertical adjustment of the leg within the eye 46.

The leg obviously passes down outside the 85 chair arm but its caster or foot 45 will not rest on the floor in this position, as still the chair attachment with the leg attached will rest on shanks 3 on the chair arms, when the chair attachment is in use for reading or 90 writing purposes. If, however, the occupant desires to leave the chair, then he can pull out shank 3 on the side to which the leg attachment is mounted to the arms 4 of the fork and set the attached leg with the caster 95 or foot 45 on the floor. In this position the chair attachment resting with one support 7 and its members on the leg, can be moved on said leg around its pivot, said pivot is the other shank 3 which still remains in the 100 other chair arm.

This leg attachment will merely be used for invalids, as normal users easily can leave the chair by pulling out one of the two shanks 3, turning the chair attachment outward around the other shank as its pivot, and then turning back the attachment and replacing shank 3 in its base. In this manner the normal user can occupy or leave the chair at any desired moment, without using 110 the leg attachment, or take the chair attachment from the chair and without taking the load from the table. All parts of this device are of the desired sizes, proportions and materials, and by preference they are ornamented appropriately so that the attachment will be an addition to the piece of furniture to which it is applied.

What is claimed as new is:—

1. In a chair attachment, the combination 120 with forks adapted to be mounted in the chair-arms, supports adjustably carried by said forks, and on each support a runner having fingers carried around the support; of hanger plates adjustably carried by said 125 runners, a table top, and two hinge connections between said top and the hangers, each comprising leaves underlying the top and other leaves connected at two points to the hangers.

2. In a chair attachment, the combination with forks adapted to be mounted in the chair-arms, supports adjustably carried by said forks and each having an upstanding body of U-shaped cross section, and on each body a runner of U-shaped cross section with fingers carried around the support; of hanger plates adjustably carried by said runners, a table top, and two connections between said top and the hangers, each comprising long leaves underlying the top and short leaves connected to the upper and lower ends of said hangers. 50
3. In a chair attachment, the combination with forks adapted to be mounted in the chair arms, supports adjustably carried by said forks and each having an upstanding body of U-shaped cross section, and on each body a runner of U-shaped cross section with fingers carried around the support; of hangers each pivoted at its upper end to one of the runners and having an arcuate slot in its body, bolts carried by the runners and passing through said slots, tightening means on said bolts, a table top, and connections between it and the upper and lower ends of both hangers. 60
4. In a chair attachment, the combination with a pair of supports adapted to be carried by the chair-arms, elements movably mounted on said supports, hangers pivotally connected with and adjustable in relation to said elements, a table top made in two panels, and channel-bars secured across the under side of the panels and hinged to each other; of hinges having long leaves adjustable in the sections of said channel-bars, and connections between the other leaves of these hinges and the hangers, substantially as described. 70
5. In a chair attachment, the combination with a pair of supports adapted to be carried by the chair-arms, elements movably mounted on said supports, hangers pivotally connected with and adjustable with relation to said elements, and a table top; of channel bars across the table top, hinges having long leaves adjustable in said channel-bars, and connections between the other leaves of said hinges and the hangers, substantially as described. 75
6. In a chair attachment, the combination with a pair of supports adapted to be carried by the chair-arms, elements movably mounted on said supports, hangers pivotally connected with and adjustable with relation to said elements and a table top in two parts; of channel-bars underlying the parts of the table top, hinges connecting said bars where said parts meet, slotted members movably mounted at their inner ends in said channel-bars and connected at their outer ends with said hangers, and set screws through said slotted members and channel-bars into the parts of the top. 80
7. In a device of the class described for application to chairs and the like, the combination with forks adapted to be mounted in the chair-arms and having angular holes through their bodies, supports carried by the forks, and the rest proper carried by the supports; of an arm of angular cross section adapted to fit in either of said holes, said arm having an eye at its outer end, a set screw in one side of the eye, and a leg passing through said eye and adapted to be held therein by the set screw, for the purpose set forth. 85
8. In a device of the class described for application to chairs and the like, the combination with forks adapted to be mounted in the chair-arms and having angular holes through their bodies, and a book rest supported by the forks; of an arm of angular cross section adapted to fit in either of said holes, and a leg adjustably mounted in the outer end of said arm so as to make contact with the floor. 90

In testimony whereof I affix my signature in presence of two witnesses.

JULIUS HEUSSER.
